UNITED STATES PATENT OFFICE.

EDGAR ANDREW NUGENT, OF UNIONVILLE, NEW YORK.

PENCIL-SHARPENER.

1,122,149.

Specification of Letters Patent. Patented Dec. 22, 1914.

Application filed October 21, 1913. Serial No. 796,437.

To all whom it may concern:

Be it known that I, EDGAR A. NUGENT, a citizen of the United States, and a resident of Unionville, in the county of Orange and State of New York, have invented a new and Improved Pencil-Sharpener, of which the following is a full, clear, and exact description.

My invention has for its object to provide a pencil sharpener which may be carried on the pencil and which serves to hold the pencil to a pocket of a garment in which the pencil is carried. The pencil sharpener is constructed with a knife which makes with an oblique cut, a long or short point as desired. This knife may be moved out of operative position when it is desired to move the pencil sharpener up from the pencil point. The sharpener forms a rest for the fingers when the pencil is used for writing.

Other objects of the invention will appear in the following specification in which the preferred form of my invention is disclosed.

In the drawings similar reference characters refer to similar parts in all the views in which—

Figure 1 is a view showing an elevation, the pencil on which my pencil sharpener is secured; Fig. 2 is a sectional side elevation of Fig. 1; Fig. 3 is a sectional plan view of Fig. 1, and Figs. 4 and 5 are views showing the position of the blades and the guide when the sharpener is used to cut the pencil point.

By referring to the drawings, it will be seen that a collar 5 is provided through which the pencil 6 is disposed, this collar 5 having an extending finger 7 which is adapted to coöperate with the pencil 6 to clamp a pocket member. By this means, the pencil may be secured to the pocket so that there will be no danger of its being lost should the person stoop down. Extending in the direction opposite to that in which the finger 7 extends there are fingers 8 which are secured to the collar 5 and which are provided with openings 9 for receiving a guide member 10. This guide member 10 has an offset 11 which is pivoted at 12 to the blade 13, the blade being pivoted at 14 to the collar 5. Disposed opposite the blade 13 and between the fingers 8 there is a finger 15, the fingers 8 and 15 being adapted to engage the sides of the pencil 6. When the pencil is being sharpened, the guide 10 is disposed through the openings 9 in the fingers 8 which hold

the blade 13 in position so that when the pencil 6 is turned relatively thereto the cutting edge 13^a on the blade 13 will cut the pencil point as may be desired. As will be seen by referring to Fig. 4 of the drawings, the blade 13 is pivoted at a greater distance from the right hand finger 8 than from the left hand finger 8, and as the guide 10 is first disposed through the opening 9 in the right hand finger 8 and then through the opening 9 in the left hand finger 8, the blade 13 is disposed obliquely relatively to the pencil. The finger 15 is provided to serve as a rest for the pencil.

After the pencil has been sharpened, the guide 10 is removed from the openings 9 in the fingers 8 and the blade 13 is rotated so that the guide 10 is raised. As will be seen by referring to Fig. 3 of the drawings, this guide 10 has a channel 11 in which the cutting edge 13^a of the blade 13 may be disposed. When the guide 10 has been moved to the position shown in Fig. 3 of the drawings, the resilient flanges 16 on the finger 7 engage, one, the rear edge of the blade 13 and the other, the guide 10 to hold the guide 10 and the blade 13 in inoperative position. The free end 13^b of the blade 13 has an enlarged portion 13^c which is adapted to engage the pencil 6 as shown in Figs. 1 and 2 of the drawings to hold the collar 5 in adjusted position.

Having thus described my invention, I claim as new and desire to secure by Letters Patent:

1. In a pencil sharpener, a member adapted to be secured to a pencil and being provided with a finger having an opening, a blade pivoted to the member, and a guide pivoted to the end of the blade and normally disposed in the opening.

2. In a pencil sharpener, a collar in which a pencil is normally disposed, a blade pivoted to the collar on an axis, which, if extended, would pass through the collar, a guide mounted on the blade and guide means on the collar for coöperating with the guide for the purpose specified.

3. In a pencil sharpener, a collar having fingers with openings extending from opposite sides of the collar, a blade pivoted to the collar, and a guide pivoted to the blade and adapted to be disposed in the openings.

4. In a pencil sharpener, a member, a blade pivoted to the member, a guide piv-

- oted to the blade and having means for protecting the edge of the blade and means on the member for holding the guide in adjusted position.
5. In a pencil sharpener, a collar having fingers extending from opposite sides of the collar and having means for holding a guide in adjusted position, a finger extending from the collar at one side of the first fingers, a 10 blade pivoted to the collar opposite the second mentioned finger, and a guide pivoted to the blade and adapted to be engaged by the said means.
6. In a pencil sharpener, a collar having fingers extending from opposite sides of the collar and having means for holding a guide in adjusted position, a finger extending from the collar at one side of the first mentioned fingers, a blade having an edge and pivoted to the collar opposite the second mentioned fingers, a guide pivoted to the blade and adapted to be engaged by the said means and means on the guide for protecting the edge of the blade.
25. 7. In a pencil sharpener, a collar, a blade pivoted to the collar on an axis, which, if extended, would pass through the collar, and means on the collar for holding the blade in operative position and relatively to the 30 collar.
8. In a pencil sharpener, a collar in which a pencil may be disposed, a finger extending in one direction from the collar and provided with means for holding a guide in adjusted position, a finger extending from the 35 collar in the opposite direction for co-acting with the pencil to grip a pocket member, a blade pivoted to the collar and a guide pivoted to the blade and adapted to be held by the said means.
9. In a pencil sharpener, a collar in which a pencil may be disposed, a finger extending in one direction from the collar and provided with means for holding a guide in adjusted position, a blade pivoted to the collar, a guide pivoted to the blade and adapted to be held by the said means, a finger extending from the collar in the opposite direction for co-acting with the pencil to grip a pocket member and flanges on the last 40 45 50 mentioned finger for engaging and holding the blade and the guide in inoperative position.

In witness whereof, I have signed my name to this specification in the presence of 55 two subscribing witnesses.

EDGAR ANDREW NUGENT.
